(57) **CLAIM**

The ornamental design for a women's modest pants skirt, as shown and described.

DESCRIPTION

FIG. 1 is a front, right, top perspective view of a women's modest pants skirt showing my new design.

FIG. 2 is a rear, right, bottom perspective view thereof.

FIG. 3 is a front elevational view thereof.

FIG. 4 is a back elevational view thereof.

FIG. 5 is a left side elevational view thereof.

FIG. 6 is a right side elevational view thereof.

FIG. 7 is a top plan view thereof; and,

FIG. 8 is a bottom plan view thereof.

The broken lines in the drawings depict stitching and form no part of the claimed design.

The design shown is not to be limited to any particular size and may be scaled larger or smaller.
